UNITED STATES PATENT OFFICE.

LEE D. CRAIG, OF SAN FRANCISCO, CALIFORNIA, ASSIGNOR TO SQUARE RULE COMPANY, A CORPORATION OF CALIFORNIA.

COMBINED FOLDING RULE AND SQUARE.

1,088,544.

Specification of Letters Patent.

Patented Feb. 24, 1914.

Application filed March 24, 1913. Serial No. 756,396.

To all whom it may concern:

Be it known that I, LEE D. CRAIG, a citizen of the United States, residing in the city and county of San Francisco and State of 5 California, have invented certain new and useful Improvements in Combined Folding Rules and Squares, of which the following is a specification.

The hereinafter described invention relates to improvements in folding rules, particularly to that type of rule employed by carpenters or the like, and the invention has for its principal objects to provide a rule of the above type which is capable of being 15 readily converted from a rule into a square to assist in scribing a line across a piece of material at right angles to the side edge thereof; to provide a rule so constructed as to be folded to form a right angle having 20 two straight edges thus dispensing with the necessity of a carpenter carrying a separate rule and square.

With the above mentioned and other objects in view, the invention consists in the 25 novel construction and combination of parts hereinafter described, illustrated in the accompanying drawings, and pointed out in the claims hereto appended; it being understood that minor changes within the scope of 30 the claims hereto appended may be resorted to without departing from the spirit of the invention.

To more fully comprehend the invention, reference should be had to the accompanying 35 drawings in which—

Figure 1 is a view of my improved rule in folded position in side elevation. Fig. 2 is an edge view with one of the end foldable sections in partly open position, disclosing 40 the quadrant shaped lug carried at the joint between the main foldable sections. Fig. 3 is a view in elevation of the side opposite the one shown in Fig. 1 of my improved rule when used as a square. Fig. 4 is a view in 45 perspective with the end foldable sections in partly open position, disclosing the joint connecting the main foldable sections and the quadrant shaped lug secured thereto.

Referring more particularly to the drawings, wherein like numerals of reference designate corresponding parts throughout the several views; the numerals 1 and 1' designate the main foldable sections of the rule, which are hinged together at one end by the 50 usual form of rule-joint, comprising an out-

wardly projecting circular tongue 2 secured to the end of the rule section 1, and the same fitting within a slot formed by the spaced outwardly projecting circular ears 3, carried by the end of the rule section 1', the tongue 2 and ears 3 being united by a pivot pin 4. Hinged to the opposite ends of the respective main foldable rule sections 1 and 1' are the end sections 5 and 6, each of the same length as the main sections 1 and 1' and 55 adapted to be folded thereon, as in Fig. 4.

Secured to the outer face of one of the ears 3 is a quadrant shaped limiting lug 7, the face 8 of which normally abuts against the end of the foldable end section 6, and the 70 face 9 of said quadrant shaped lug is adapted, when the main rule sections 1 and 1' are pivoted at right angles to each other, as in Fig. 3, to abut against the free end of the foldable end section 5, should the same be in 75 its folded position, and the rule sections when in this position forming a true square, as in Fig. 3. A portion of the tongue 2 and ears 3 is respectively cut away, as at 10 and 11, to provide a true right angle corner at 80 the pivotal joint of the main rule sections 1 and 1', when the same are in the position as shown in Fig. 3.

When it is desired to extend the rule to its full length with the main rule sections 1 and 1' in alinement with each other, it is only necessary to raise the end rule section 5, which will permit the face 9 of the quadrant shaped lug 7 to pass the end of the end section 5 and to swing with the ear to which the 85 same is secured.

It will be observed that in my invention I have provided a rule with a simple attachment which enables the same to be used as a 90 square.

Having thus described my invention what I claim as new and desire to protect by Letters Patent is:—

1. In a folding rule of the class described, the combination with a pair of main rule 100 members, a hinge connecting said rule members at one end, said hinge permitting movement of said main rule members in alinement with each other and also permitting movement of said main rule members to a 105 position parallel with each other, end rule members hinged to the free end of each of said main rule members and capable of folding thereon, and a lug carried by said first mentioned hinge and having a stop face ex- 110

posed for contact with the free end of one of said end rule members when the same is in its folded position on the main rule member, and the latter is swung away from the other 5 main rule member, to limit the movement of the main rule sections intermediate the first two mentioned positions.

2. In a folding rule of the class described, the combination with a pair of main rule 10 members, a hinge connecting said rule members at one end, said hinge permitting movement of said main rule members in alinement with each other and also permitting movement of said main rule members to a 15 position parallel with each other, end rule members hinged to the free end of each of said main rule members and capable of fold-

ing thereon, and a lug carried by said first mentioned hinge and having a stop face exposed for contact with the free end of one of 20 said end rule members when the same is in its folded position on the main rule member, and the latter is swung away from the other main rule member, and a face exposed to abut with the end of the other of said end rule member when in its folded position, substantially as described.

In testimony whereof I have signed my name to this specification in the presence of two subscribing witnesses.

LEE D. CRAIG.
